UNITED STATES PATENT OFFICE.

WILLIAM E. COONEY, OF PITTSBURGH, PENNSYLVANIA.

GAME APPARATUS.

Application filed May 23, 1923. Serial No. 640,864.

To all whom it may concern:

Be it known that I, WILLIAM E. COONEY, a citizen of the United States, residing at Pittsburgh, county of Allegheny, and State 5 of Pennsylvania, have invented a new and useful Improvement in Game Apparatus, of which the following is a full, clear, and exact description.

The present invention relates to game apparatus, and more particularly to an apparatus for playing a marine game.

An important object of the invention is to provide a game apparatus by means of which mock contests between vessels may be 15 staged.

Another object of the invention is to provide a game apparatus which may be readily learned either by adults or children, and which will furnish amusement to both.

20 In the accompanying drawings, I have shown, for purposes of illustration only, certain embodiments of my invention, it being understood that the drawings do not define the limits of the invention, as changes 25 may be made in the disclosure thereof without departing from the spirit of the invention or scope of the claims.

In the drawings:

Figure 1 is a plan view of a board or 30 chart adapting the game to be played by as many as six players,

Figure 2 is a view similar to Figure 1, showing a portion of a board adapting the game to be played by as many as eight 35 players,

Figure 3 is a perspective view of one of the pieces, and

Figure 4 is a perspective view of another type of piece.

40 The chart shown in Figures 1 and 2 represents a body of water having lanes for determining the paths of travel of the pieces of the opposing players.

In Figure 1 there are three starting paths 45 A at each end of the board, whereas in Figure 2 there are four starting paths A at the end of the portion of the board shown, it being understood that the other end of the board also has four starting paths. Ob-

50 Obviously, any suitable number of starting paths may be provided, depending upon the maximum number of players that it is desired may be permitted to play the game at any one time.

55 The starting paths lead to havens of safety B, and intermediate the havens B are other

havens C. The various havens B and C are interconnected by paths D. The various paths are divided into spaces, and these spaces may, for convenience, be numbered. 60

Each player will be provided with a number of pieces E, preferably three, representing vessels, and a single piece F representing a chaser, the pieces E representing vessels permitted, in accordance with the 65 rules of the game as hereinafter explained, to move in one direction only along the various paths, and the piece F representing a vessel permitted to move in either direction along the paths, backwards or forwards. 70 The pieces E may be conveniently provided with an arrow or other indicia thereon to indicate the direction of travel.

Of course, it will be understood that the 75 pieces need not necessarily represent vessels, but since the chart illustrated represents paths through a body of water, it is appropriate that the pieces represent vessels.

The pieces of the different players may be 80 distinguished from each other, as by coloring them differently.

In playing the game, the players may play independently or they may form partnerships as desired. Each player preferably selects a different starting path for 85 entering his pieces into the game. As previously stated, the various paths are divided into spaces, and the players move their pieces along the paths the number of spaces indicated by a suitable chance 90 device, such as a spinning device G shown in Figure 1. As shown therein, the spinning device consists of a dial painted on the board or chart and a rotatable arrow adapted to be given a spinning motion in the 95 usual manner. This spinning device may, if desired, be made entirely separate from the board or chart, or some other chance device may be employed, such as a die.

In starting the game, the several players 100 spin the arrow in turn and move one of their pieces over their respective starting paths the number of spaces indicated on the dial. The object of the game is for the players to capture each other's pieces 105 until finally only one player has any pieces left on the chart or board, that player being the winner.

The players spin the arrow in succession 110 and move their pieces the number of spaces indicated on the dial. After a player has entered a piece into the game, he may enter

his other pieces at such times as he may see fit.

The pieces E are permitted to move in one direction only along the various paths. 5 In other words, if a piece E is moved in a forward direction along the path, that piece may not be moved in the opposite direction along that path. The piece F, hereinbefore called a chaser, may, however, move in 10 either direction along a path. This gives the piece F a much greater range of operation than the pieces E. If a player has a piece E on a certain space on a certain path, that piece may be captured by the 15 piece of another player. For example, suppose the piece of one player is on the space of a path numbered 5 and the piece of another player is on the space of the same path numbered 1, and the latter player spins the 20 arrow and, as a result, is entitled to move exactly four spaces. In that case, the second player may move his piece to the space occupied by the piece belonging to the first player, and remove the latter piece from the 25 chart. The piece of a player cannot be captured while that piece is occupying a haven of safety. For example, suppose the piece of a player is on the space numbered 3 of the starting path A, and his next move entitles him to move four spaces. In that 30 case, he could move his piece on to a space B (haven of safety), and this piece could not then be captured by the piece of an opponent so long as it remained on that space. In 35 view of the fact that the pieces F (chasers) are permitted to move in either direction along a path, it will be obvious that these pieces may be used to capture the pieces of an opponent much more readily than the 40 pieces E.

The players continue to move their respective pieces in turn, capturing one another's pieces, until finally only the pieces of one player remain on the chart or board,

that player being the winner of the game. 45 As already stated, the players may play the game independently, or they may form partnerships. In the case of partnerships, the partners are entitled to move each other's pieces. 50

The advantages of the present invention arise from the provision of a game apparatus which may be played by young or old, and which will furnish amusement to both. 55

I claim:

1. A game apparatus comprising a chart representing a water area, and having a plurality of paths divided into spaces, certain of said paths representing starting paths, the spaces of said paths being numbered, a plurality of spaces representing havens of safety and interconnected by said paths, and a plurality of pieces for each player, certain of said pieces representing vessels permitted to move in one direction only along the several paths and certain others thereof representing vessels permitted to move in either direction along said paths, substantially as described. 65

2. A game apparatus comprising a chart representing a water area, and having a plurality of paths divided into spaces, including a plurality of starting paths at each end of the chart each leading to a space representing a haven of safety and a plurality of paths running in different directions and interconnecting said havens of safety and leading to other spaces representing havens of safety, and a plurality of pieces for each player, certain of said pieces representing vessels permitted to move in one direction along the several paths and certain others thereof representing vessels permitted to move in either direction along said paths, substantially as described. 70 75 80

In testimony whereof I have hereunto set my hand.

WILLIAM E. COONEY.
